PHILIP SUBKOW, OF LOS ANGELES, CALIFORNIA, ASSIGNOR TO UNION OIL COMPANY OF CALIFORNIA, OF LOS ANGELES, CALIFORNIA, A CORPORATION OF CALIFORNIA

HIGH VACUUM STEAM DISTILLATION

Application filed March 7, 1928. Serial No. 259,690.

This invention relates to a process and apparatus for vacuum distillation, particularly to a process and apparatus for steam distillation under very high vacuum, that is, under 5 very low absolute pressure.

It is well known that in ordinary vacuum distillation, the absolute pressure maintainable in the still is in part determined by the vapor pressure which exists at the terminal 10 receiver immediately preceding the vacuum pump. Thus the minimum pressure maintainable in this receiver will determine the vacuum in the system. This pressure is evidently the vapor pressure of the condensate 15 at the temperature in the terminal receiver. In steam distillation of materials to produce relatively high boiling point distillates, as in the distillation of lubricating oils, the final condensate which must be produced is wa- 20 ter. When this distillation occurs at very low pressures in the neighborhood of a few millimeters of mercury, it is essential to provide means in the terminal receiver of con- 25 densing the steam at this pressure and to maintain the pressure of the water in the re- ceiver by sufficiently cooling the condensate so as to produce a vapor pressure below the 30 desired pressure. However, in order to maintain the vapor pressure of the steam con- densate such as to maintain this very low 35 vacuum, the water must be cooled to very low temperature. Thus, at very low pres- 40 sures in the neighborhood of 5 mm. a tem- perature at the freezing point of water would be required. However, if the steam is 45 condensed by use of ordinary cooling water, the average temperature of the condensate would be 100° F. and perhaps higher. This is de- 50 termined by the available cooling water tem- perature and the proportion of steam con- densed. Where water is obtained from cool- 55 ing towers as is usual, temperatures of less than 100° F. are very costly to maintain. At 60 a 100° F. temperature the vapor pressure of water is 50 mm.

It is the object of this invention to ob- 65 viate the difficulties enumerated above. The object is to make possible high vacuum dis- 70 tillation with steam without excessive cooling 75 of the condensate, and, in fact, to use only

such cooling water as is available at the plant. In further discussion, the term "available cooling water temperature" will be defined as being that temperature which is obtainable by using a cooling water available at the 55 plant where the process is operated when such cooling water is used in conventional methods either by direct contact with the steam or by intermediate heat exchange.

The invention is directed to a high vacuum 60 steam distillation whereby means is provided to condense the steam at available cooling wa- ter temperature.

This invention is particularly directed to a method and apparatus for high vacuum 65 distillation of mineral oil below approxi- 70 mately 25 mm. whereby the residual steam is scrubbed to form a solvent-water mixture which will have a vapor pressure at or be- 75 low 25 mm. the temperature of the condensate being obtained by means of available cooling water.

The process and apparatus will be better 75 understood by reference to the accompany- 80 ing drawing which illustrates the specific em- bodiment, illustrative, but not limiting the invention.

The figure shows a schematic embodiment 85 of one form of the apparatus for carrying 90 out the process in this application.

In the drawing, 1 is a charging line for liquid to be distilled, in this case lubricating oil stock. The oil is fed to 1, under the de- 95 sired pressure, steam may be mixed with this oil if desired by injection through line 1a. The oil is passed to coil 2, in furnace 3, where it is raised to the desired distilling tempera- 90 ture. The heated oil is passed through line 4, this passage being regulated by valve 5. Valve 5 may be operated to create any desired 95 back-pressure on line 4. Steam may be ad- mitted by line 4a, regulated by valve 5a. The pre-heated feed is then distilled in vaporizing tower 8. Part of the oil is immediately vaporized on expansion through spray 6, the un-vaporized oil trickles over obstructions, such as tile, and meets an upward stream of steam introduced through 10. The introduc- 100 tion of steam is regulated at 1a, 5a, and 10. The unvaporized material is withdrawn

through 12, by means of a pump, or if the vaporizer is set at a barometric level above ground, it may be discharged through a barometric leg. The resulting vapors pass 5 through mist separator 9, which acts to separate the mechanically entrained unvaporized material. The resulting vapors pass into the top section 7, and through line 11, to a series of fractional condensers 13, cooled by 10 oil, steam or water, as the case may be, introduced through 14 and exiting through 15. The partial condensates are withdrawn through 16, into collecting tanks 17, and withdrawn through 18, by means of pumps, or if 15 these condensers are set at barometric level, the discharge may be through barometric legs.

The unvaporized portion, in this case substantially steam, passes through barometric 20 condenser 20, where it meets the stream of scrubbing liquid adapted to dissolve the steam introduced through line 21. The uncondensed material, usually fixed gases or light volatile oils, is withdrawn through line 25 22, by high vacuum pump 23. The scrubbed liquid containing the condensed steam passes down to barometric leg 24, into sump 25, from which it is withdrawn through 26, by a pump, passes through heat exchanger 27, 30 and through line 28, and spray 29, into the vaporizing or exhausting tower 30. The material trickles over obstruction 31, adapted to film the material, and meets an upward current of steam or hot combustion gases introduced through 32. The evaporated water exits 35 through 33. Tower 30 may be under vacuum if desired. The hot, concentrated material is withdrawn through 34, by a pump and passed through 27, in heat exchange with the liquid 40 passed through 26. The liquid then passes to cooler 36, where it is cooled by available cooling water, introduced through 37 and exiting through 38, to a temperature as to produce the desired condensation effect when introduced through 21. The steam jet or blower 45 39 positioned in line 19, is used when it is desired to raise the pressure in the barometric condenser. Part of the material is by-passed through 40, the amount being controlled by 50 valves 41 and 42, through cooler 36 to the condenser 20. The recirculation of this material helps to control the condensation in 20 by maintaining the correct amount of solvent fluid and also helps to saturate the solvent. 55 Obviously, however, by closing 42, the material may be sent in a single pass, if this is found desirable and economical. The apparatus is so constructed to minimize friction losses and leaks as will be understood by those 60 skilled in this art.

As a specific example illustrating this process in its preferred embodiment, the following may be given:

Lubricating oil stock is introduced into coil 65 2, together with steam and heated to about

600° F. and introduced into 8. Steam may be introduced via 5_a to aid in flashing the oil. Steam also may be introduced via 10 to aid in the distillation. The pressure is maintained in the tower 8, preferably at not over 25 mm. 70 In the specific example, the pressure is maintained at 20 mm. The proportions of the steam and oil are such as to give the steam a partial pressure of 15 mm. and the oil 5 mm. In other words, the steam is $\frac{3}{4}$ of the volume 75 of generated vapors in the space 7.

Oil is condensed in 13 fractionally, and steam passes through 19 to condenser 20. Scrubbing liquid such as glycerine is circulated through 21. The temperature and 80 volume are controlled so as to maintain the concentration and temperature of the mixture thus formed to give the desired vapor pressure. This will be determined by the pressure drop through the apparatus, and by the 85 pressure desired to be maintained in the barometric condenser. Thus, if the temperature maintainable in the barometric condenser be 100° F. then the approximate concentration required to give 16 mm. pressure in the condenser will be 64% glycerine-36% water by volume. At concentration of 72% glycerine and 28% water by weight, the vapor pressure will be 8 mm. at 100° F. A concentration of 90 56% glycerine and 44% water by volume will 95 give a vapor pressure of 23 mm. at 100° F. If a salt is used in concentration for example of 100 grams calcium chloride in 100 grams water the mixture will give a vapor pressure of 11 mm. Instead of using calcium one may 100 use KOH or other electrolyte, which depresses the vapor pressure of water. By regulating the temperature and concentration of the mixture formed in the condenser the desired vapor pressure may be obtained. Knowing 105 the volume of steam and its temperature, and the required resultant pressure in this condenser, the concentration, volume and temperature of the scrubbing liquids can be 110 readily adjusted.

As an auxiliary method, a partial compression of the vapors may be obtained by introducing the steam jet in line 19. This will raise the pressure in 20, as is well known, and will increase the allowable concentration of water 115 in the condensate mixture. Thus, if the booster be operated to overcome the back-pressure of the resistance so as to maintain a uniform pressure throughout the whole apparatus, i. e. to maintain, for instance 25 mm. in the barometric condenser, the concentration of the glycerine in the mixture is 54% by volume, assuming a temperature of 100° F. in the barometric condenser, and the vapor pressure of water at 79° F. is 25 mm.

The condensate is removed through line 26, and sent to evaporator 30. If a salt solution is used, a conventional salt evaporator may be employed. In the example given, the apparatus described is best adapted to the use of 120 125 130

glycerine, although any well known apparatus for concentrating glycerine may be employed. The glycerine-water mixture is passed through heat exchanger 27, and introduced into tower 30, where it is distilled by a stream of combustion gas to de-water the glycerine. Steam may be used in its place, or the glycerine may be heated in a tube still before introduction into the tower 30. Provision may be had for refluxing the glycerine which may be evaporated. Likewise the evaporator may be operated under vacuum. From the description anyone skilled in the art will be able to concentrate the scrubbing agent.

The de-watered scrubbing agent is passed through heat exchanger 27, and to cooler 36. In cooler 36 care must be taken that the temperature is not lowered so low that the glycerine freezes or that salt crystallizes out, if a salt solution is employed. Thus the cooling and concentration is controlled to give the optimum concentration to effect the necessary concentration in the barometric condenser without crystallizing in the cooler. In the specific example given above, the cooling water may vary from 50-80° F. in which case, there is no danger of glycerine freezing especially if it carries a little water.

While the specific example describes the use of absolute pressure at 20 mm., it will be understood that the absolute pressure may be lowered as far as possible (as far as 1 or 2 mm. or less), and above 25 mm. as the exigencies of the operation demand. The process as described is very flexible. While glycerine and calcium chloride solution have been specifically mentioned, any liquid of relatively high boiling point and sufficient water solubility will be applicable. Any one skilled in the art will be able to choose the requisite material to suit particular conditions. It is believed that glycerine is best suited. Various salts are available. The principle here is the reduction of vapor pressure by the salt as will be understood by those skilled in the art. The fundamental principle of lowering the vapor pressure of water by a solute is well understood by those skilled in this art.

The above explanation is not to be taken as limiting my invention, but descriptive of the best modes of employing my invention, which I claim to be:

1. A method of high vacuum steam distillation comprising distilling oil with steam at high vacuum, condensing the steam and lowering the vapor pressure of the steam condensate formed in said condensation by a solute below the vapor pressure of water at the temperature at which the steam is condensed.

2. A method of high vacuum steam distillation comprising distilling oil with steam at high vacuum, condensing the resulting oil vapors without condensing the steam, and sub-

sequently condensing the steam and lowering the vapor pressure of the steam condensate formed in said condensation by a solute below the vapor pressure of water at the temperature at which the steam is condensed.

70

3. A method of high vacuum steam distillation which comprises steam distilling oil at high vacuum, condensing the oil vapors, scrubbing the steam with a solvent, maintaining the temperature and concentration of the mixture thus formed to maintain the mixture at a vapor pressure less than the vapor pressure of water at the temperature of the mixture.

75

4. Method of steam distilling oil under high vacuum which comprises vaporizing oil with steam at high vacuum, condensing the oil vapors thus generated without condensing the steam, scrubbing said steam vapors with a solvent, maintaining the pressure of the mixture below the vapor pressure of water at the temperature obtainable by use of available cooling water.

85

5. Method of distilling oil at an absolute pressure not greater than 25 mm. mercury with steam, which comprises vaporizing oil with steam at an absolute pressure not greater than 25 mm. mercury, condensing the oil vapors without condensing the steam and condensing the steam in the presence of a solute capable of lowering the vapor pressure of water at an absolute pressure not greater than 25 mm. and at a temperature obtainable by available cooling water.

90

6. Method of high vacuum steam distillation which comprises distilling oil with steam under high vacuum, condensing the oil vapors but not the steam, increasing the pressure of the steam and scrubbing the steam with solvent capable of reducing the partial pressure of the water in the condenser so as to maintain the vapor pressure of the mixture, at available cooling water temperature, not greater than the last mentioned steam pressure.

100

7. Method of high vacuum steam distillation comprising distilling oil with steam at high vacuum, condensing the resulting oil vapors without condensing the steam, scrubbing the steam with a solvent at a temperature not less than the available cooling water temperature and at an absolute pressure less than the vapor pressure of water at said cooling water temperature, removing the solvent water mixture, evaporating water from said solvent, cooling said solvent by heat exchange with available cooling water, and scrubbing further steam with said solvent in cyclic operation.

105

8. Method of distilling oil at a pressure not greater than 25 mm. with steam, which comprises vaporizing oil with steam at an absolute pressure not greater than 25 mm. mercury, condensing the oil vapors without condensing the steam, scrubbing the steam with

115

120

125

130

a solvent at a temperature not less than 79° F. and an absolute pressure not greater than 25 mm., evaporating water from the solvent, cooling the solvent and re-introducing said 5 solvent into said steam.

9. A method of high vacuum distillation of oil which comprises steam distilling oil at a low absolute pressure, cooling the steam to a temperature insufficient to condense the 10 same at the low absolute pressure maintained thereon, and condensing the steam at said last mentioned temperature and pressure by lowering the vapor pressure of the condensate thereof by introducing into said condensate a 15 material which will lower the vapor pressure of said condensate.

10. A method of high vacuum distillation of oil which comprises steam distilling oil at a low absolute pressure, fractionally separating the oil by not condensing the steam, cooling the steam to a temperature insufficient to condense the same at the low absolute pressure maintained thereon, and condensing the steam at said last mentioned temperature 25 and pressure by lowering the vapor pressure of the condensate thereof by introducing into said condensate a material which will lower the vapor pressure of said condensate.

11. A method of high vacuum distillation 30 of oil which comprises steam distilling of oil at a low absolute pressure, fractionally separating the oil but not condensing the steam, cooling the steam to a temperature of itself insufficient to condense the steam at the pressure 35 maintained thereon by contacting said steam with a solvent and thus condensing the steam at the said pressure and temperature.

12. A method of high vacuum distillation of oil which comprises steam distilling oil at 40 a pressure not exceeding approximately 25 mm. absolute pressure, fractionally separating the oil but not condensing the steam, contacting the steam with a solvent at a pressure not exceeding 25 mm. mercury and cooling 45 the steam to a temperature not less than 79° F. and thus condensing the steam at the resultant temperature and pressure.

13. A method of high vacuum distillation 50 of oil which comprises steam distilling of oil at a low absolute pressure, fractionally separating the oil but not condensing the steam, cooling the steam to a temperature of itself insufficient to condense the steam at the pressure 55 maintained thereon by contacting said steam with a solvent and thus condensing the steam at the said pressure and temperature, removing the solvent-water mixture, evaporating the water from the solvent, cooling the solvent and re-introducing the solvent 60 into the steam to be condensed, in cyclic operation.

14. A method of high vacuum distillation 65 of oil which comprises steam distilling oil at a pressure not exceeding approximately 25 mm. absolute pressure, fractionally separat-

ing the oil but not condensing the steam, contacting the steam with a solvent at a pressure not exceeding 25 mm. mercury and cooling the steam to a temperature not less than 79° F. and thus condensing the steam at the resultant temperature and pressure, removing the solvent water mixture, evaporating the water from the solvent, cooling the solvent and re-introducing the solvent into the steam to be condensed, in cyclic operation. 75

15. An apparatus for high vacuum distillation comprising a still, a condenser, means for maintaining high vacuum in the still and in the condenser, means for introducing a scrubbing liquid into the condenser, means for withdrawing the scrubbing liquid from the condenser, an evaporator, means for introducing the scrubbing liquid into the evaporator, means for withdrawing the scrubbing liquid from the evaporator, a cooler, means for passing the scrubbing liquid from the evaporator through the cooler and to the condenser. 80

16. A method of high vacuum steam distillation which comprises distilling oil at a 90 low absolute pressure with steam, condensing the steam at a low absolute pressure by scrubbing the same with a liquid, evaporating the water from the mixture thus formed, and re-introducing the regenerated liquid to condense further steam in cyclic operation. 95
